UNITED STATES PATENT OFFICE.

GEORGE C. WORTHINGTON, OF ELYRIA, OHIO, ASSIGNOR TO THE WORTHINGTON BALL COMPANY, OF ELYRIA, OHIO, A CORPORATION OF OHIO.

DESIGN FOR A PLAYING-BALL.

45,082.

Specification for Design.

Patented Dec. 23, 1913.

Application filed September 29, 1913. Serial No. 792,527. Term of patent 7 years.

To all whom it may concern:

Be it known that I, GEORGE C. WORTHINGTON, a citizen of the United States, residing at Elyria, in the county of Lorain and State of Ohio, have invented a new, original, and ornamental Design for a Playing-Ball, of which the following is a specification, reference being had to the accompanying drawing, forming a part thereof.

The figures show my improved design.

Figure 1 is a plan view of a ball showing an embodiment of my design. Fig. 2 is an elevation of the embodiment shown in Fig. 1.

I claim:

The ornamental design for a playing ball as shown.

GEORGE C. WORTHINGTON.

Witnesses:

H. C. BARBOUR,
F. O. RICHEY.
